UNITED STATES PATENT OFFICE.

EDWARD M. SMITH, OF DOWNEY, CALIFORNIA.

TUG WHEEL FOR OIL WELLS.

1,413,879.

Specification of Letters Patent. Patented Apr. 25, 1922.

Application filed April 28, 1921. Serial No. 465,142.

To all whom it may concern:

Be it known that I, EDWARD M. SMITH, a citizen of the United States, residing at Downey, in the county of Los Angeles and 5 State of California, have invented a new and useful Tug Wheel for Oil Wells, of which the following is a specification.

This invention relates to oil well drilling and producing apparatus and particularly to 10 apparatus used in raising the tools or pipe used in drilling or in the subsequent production of oil.

It is an object of my invention to provide 15 a tug wheel which will be of much more durable construction than the ordinary types of tug wheels which are commonly constructed of wood.

In the present practice of well drilling hoisting drums or bull wheels, are driven 20 by bull ropes running in grooves provided therefor in the tug wheel. The tug wheels are of considerable diameter and it has been customary to construct them of wood in order that they have a high coefficient of 25 friction and that their weight may not be excessive.

Further objects of my invention are the provision of a tug wheel which may be of such construction that it may be easily 30 mounted upon a standard band wheel, and which will have the added feature of expedient renewal of the wearing parts.

A further object of the invention is to provide a tug wheel having grooves with 35 a high coefficient of friction and which is made of a fire proof and heat resisting material.

A further object is to provide a tug wheel that will not cause excessive wear on the 40 rope.

With reference to the drawing which is for illustrative purposes only:

Fig. 1 is a view of a drilling rig with a 45 tug wheel of my invention applied thereto.

Fig. 2 is a vertical cross-section through a band wheel having mounted thereon a tug wheel embodying my invention.

Fig. 3 is a perspective view of one of the 50 tug wheel frame sections and of one of the spacing cant blocks I employ.

Fig. 4 is a perspective view of several of the grooved fire proof segments which are adapted to be mounted in the frame sections.

As shown in Fig. 1 of the drawing, a tug

wheel 11 of my invention is mounted on a 55 band wheel 12 driven by a belt 13 from an engine not shown. A bull rope 15, running over the tug wheel 11, drives a bull wheel 16. This arrangement gives a very flexible drive which is desirable in the hoisting of 60 great lengths of cable and drilling apparatus.

The remaining figures of the drawing illustrate the construction of a preferred form of the tug wheel 11. The band wheel 65 12, as in present practice, is constructed of a laminated wooden web 20 upon which are mounted wood cants 21 forming a rim 22. The tug wheel is comprised of semi-circular frame channel sections 25 which are bolted 70 together, by means of bent up lips 26, to form a complete wheel. In these frame sections 25 are mounted segments 30 of vulcanized asbestos, or other non-inflammable substance, and provided with grooves 31 to receive the 75 bull rope 15.

Tug wheel 11 is easily mounted on the band wheel 12 by bolts 32 which pass through spaced holes 33 in the flanges 34 of the frame channels, and through correspondingly spaced holes 35 in the asbestos segments 30. Cant blocks 40, having holes 41 spaced to accommodate the bolts 32, are provided between the frame sections 25 and the web 20 of the band wheel 12 to bring 85 the grooves 31 of the tug wheel 11 into a position beyond the confines of the band wheel rim 22.

I desire to call especial attention to the ease with which the tug wheel 11 may be mounted 90 upon the band wheel 12, and the ease with which the wearing parts, consisting of the asbestos segments 30, may be removed and replaced by new segments by taking out the bolts 32.

I claim as my invention:

1. In combination, with the band wheel of an oil well derrick, a tug wheel comprising: a channel shaped metal retaining member secured to the side of the band wheel 100 with the flanges of the channel projecting outwardly; wood cants between said channel shaped metal retaining member and said band wheel; removable friction segments fitting between the flanges; and bolts passing through said flanges, said segments, said wood cants, and the band wheel for securing 105 all of said parts together.

2. In a tug wheel, the combination of a retaining member; and vulcanized asbestos blocks secured in said member and grooved to receive the bull rope.
- 5 3. In a tug wheel, the combination of a retaining member; and removable blocks of fire proof and heat resisting material carried

in said member and grooved to receive the bull rope.

In testimony whereof, I have hereunto set 10
my hand at Los Angeles, California, this
19th day of April, 1921.

EDWARD M. SMITH.
